UNITED STATES PATENT OFFICE.

JESSE W. DANN, OF COLUMBUS, OHIO.

MACHINE FOR THE MANUFACTURE OF FELLIES.

SPECIFICATION forming part of Letters Patent No. 397,900, dated February 19, 1889.

Application filed November 21, 1883. Serial No. 112,340. (No model.)

To all whom it may concern:

Be it known that I, JESSE W. DANN, a citizen of the United States, residing at Columbus, in the county of Franklin and State of Ohio, have invented certain new and useful Improvements in Machines for the Manufacture of Fellies, of which the following is a specification, reference being had therein to the accompanying drawings, in which—

10 Figure 1 is a plan, and Fig. 2 an end elevation, of a planing-machine adapted to practice in part my method. Fig. 3 is a detail of the felly-guide in perspective; Fig. 4, a felly-strip in the condition in which it leaves the machine; Fig. 5, a portion of a felly made in accordance with my method, and Fig. 6 a similar portion of a felly made in accordance with the old method.

15 Like letters refer to like parts in all the figures.

Heretofore fellies have been bent to the desired form and subsequently beveled and finished by a planing-machine specially constructed for the purpose, or finished by hand-tools, and in either case there is a difficulty in producing a perfect product in that the fibers on the inner face and the edges of the same are in the process of bending roughened and corrugated, as shown in Fig. 6, by reason of 20 the uneven condensation of the fiber, and when in this condition the process of beveling by planing-tools, either machine or hand, tends to tear out portions of the condensed fiber, forming upon the inner or upper surface, f' , 25 of the felly indentations, depressions, or pockets, and the process, aside from being difficult and harder on the tools employed, by reason of the corrugations formed in the bending process, produces a felly the inner or upper 30 surface of which presents a variegated grain, the upper portions of the corrugations only being removed, and a smooth perfect grain is producible only by cutting clear below the condensed grain, resulting in increased waste 35 of material and labor, as well as a consequent increased cost of manufacture. The product of old methods is therefore distinguishable by its roughened transversely corrugated and pitted inner or upper surface, and, as herein- 40 after specified, the product of my improved

method is distinguishable by its smooth inner or upper surface, having an uninterrupted natural grain lengthwise and free from corrugations, pits, and depressions, as shown in Fig. 5. I have discovered a method whereby 55 the objectionable features of fellies as heretofore made are avoided, and said method consists in beveling the felly-strip before it is bent.

My invention also consists in certain means 60 for beveling the strips, as hereinafter described, and specifically set forth in the claims.

A represents the bed of a planing-machine, having the cutter-roll B and feed-rolls C D, 65 all of the usual construction.

E is a form or pattern-bed, provided with longitudinal grooves E' E², the former being of such contour as to receive a square strip and (the bottom and sides of said grooves being inclined) to present the upper surface of 70 said strip in an inclined position, so that when the form or pattern-bed with a strip in the groove is passed through the planer said upper surface of the strip is planed off angularly, thus producing one of the beveled sides 75 f of the felly-strip and felly F. The bottom of the groove E² is inclined at a greater angle than the groove E', so that when the strip F is turned end for end and the beveled side placed downward in the groove E² and passed through 80 the planer with the form or pattern-bed the upper square side is beveled to the same angle as the opposite side.

So far as the means of producing the beveled sides of the felly are concerned, they are 85 independent of the method hereinafter set forth, and I deem it proper to state that said method is not in the least dependent upon the means thus far described, as the strip may be beveled by any suitable means, the time in 90 the process or method at which the beveling is done being the essential features, rather than any means for producing the bevel.

I take a thoroughly dry and seasoned, sawed, planed, or dressed strip of suitable proportions and first bevel the opposite sides thereof. I then by any well-known means bend said beveled strip to the desired shape for a felly.

I find that a dry or seasoned strip will retain the shape to which it is bent better than 100

stock which is not dry and seasoned, and I have found by experience great difficulty in beveling fellies after they are bent, by reason of the swelling, crimping, and roughening of the grain by the bending process, and I find, also, that the preliminary dressing and beveling of the strip produces a felly which is free from pits, variegated or changeable grain, and transverse corrugations, and that in fitting fellies so made in wheels there is less labor required, and a smooth and uniform grain to work upon, and not much liability in the grain to chip or tear out.

I do not claim, broadly, any features of the well-known planing-machine herein shown, except as a part of the combined implements which I employ.

Having described my invention, what I claim is—

20 1. A planing-machine form or pattern-bed having a series of grooves, the bottoms and walls each of which are inclined at different angles to each other in each groove, substantially as specified.

2. The combination, with a wood-planing machine, of a form or pattern-bed having a groove deeper on one side than on the other and an inclined bottom, and adapted to present one side of a square strip, and also a groove having a less inclined bottom and 30 adapted to present a beveled strip angularly to the cutter thereof, substantially as shown and described.

3. The combination of the cutter-head B, feed-rolls C, bed A, and between said feed-rolls the form or pattern-bed E, having the grooves E' E², the angles formed by the sides and bottom of which differ in inclination, substantially as shown and described.

In testimony whereof I affix my signature in 40 presence of two witnesses.

JESSE W. DANN.
